US0D1040773S

(12) **United States Design Patent** (10) Patent No.: **US D1,040,773 S**
(45) Date of Patent: ** Sep. 3, 2024

(54) **VIDEO DELIVERY DEVICE**

(71) Applicant: **Charter Communications Operating, LLC**, St. Louis, MO (US)

(72) Inventors: **Ethan Miller**, Parker, CO (US); **Ian Ruppert**, Denver, CO (US); **Chelsea Young**, Englewood, CO (US)

(73) Assignee: **Charter Communications Operating, LLC**, St. Louis, MO (US)

(**) Term: **15 Years**

(21) Appl. No.: **29/835,461**

(22) Filed: **Apr. 19, 2022**

(51) LOC (14) Cl. **14-03**

(52) U.S. Cl.

USPC **D14/125**

(58) **Field of Classification Search**

USPC D14/125, 126, 129, 130, 133, 149, 159, D14/167, 172, 217, 221, 204, 209.1, 225, D14/226, 238.1, 240, 308, 348, 349, 356, D14/358, 432, 496, 511, 239; D13/103, D13/107, 108

CPC H04R 1/02; H04N 7/15; H04N 7/152; H04M 3/567; H05K 5/00; H05K 5/03

(57) **CLAIM**

The ornamental design for a video delivery device, as shown and described.

DESCRIPTION

FIG. 1 is a top left perspective view of the video delivery device.

FIG. 2 is a front view of the video delivery device.

FIG. 3 is a back view of the video delivery device.

FIG. 4 is a right side view of the video delivery device.

FIG. 5 is a left side view of the video delivery device.

FIG. 6 is a top view of the video delivery device.

FIG. 7 is a bottom view of the video delivery device.

FIG. 8 is a top right perspective view of the video delivery device; and,

FIG. 9 is a bottom left perspective view of the video delivery device.

The broken lines shown in FIGS. 1-9 represent portions of the video delivery device that form no part of the claim.

1 Claim, 7 Drawing Sheets
